MUFFLER

Herbert S. Powell, Utica, N. Y.

Application April 1, 1938, Serial No. 199,509

2 Claims. (Cl. 181—59)

The present invention relates to new and useful improvements in mufflers, and more particularly to improvements in mufflers which are generally used for quieting the noise incident to the exhaust from internal combustion engines.

The present invention is concerned with the provision of a muffler of the type wherein one or more tubes extend partially or wholly through the muffler casing. In this type of muffler, the most usual forms are the "straight-through" type or the "tri-flow" type. In the first type, there is generally provided a perforated tube, which extends substantially through the muffler casing. Baffle plates are provided around the tube so as to provide a plurality of expansion compartments for the gases passing through the muffler. Thus, the exhaust gases pass into the perforated tube and are successively expanded in the compartments during the passage thereof through the muffler to the outlet end. In the second type, a plurality of tubes are generally mounted within the muffler casing in parallel relationship so that the exhaust gases pass in a sinuous and reversely directed path through the muffler. In this type of muffler, there are also provided baffle plates around the tubes and secured to the muffler casing for affording compartments into which the exhaust gases are successively expanded as they pass through the various tubes in the casing. The present invention is specifically concerned with the provision of a muffler which combines the advantageous features of both of the above types of mufflers.

An object of the present invention is to provide a muffler which is of relatively simple construction, which is inexpensive to manufacture, and which effects the desired quieting of the exhaust gases.

A further object of the invention is to provide a muffler of the above type, wherein a plurality of relatively short tubes are mounted within the muffler casing, the adjacent ends of the tubes being offset with respect to one another so as to cause the gases to pass through the muffler in a sinuous path.

A still further object of the invention is to provide a muffler of the above type, wherein the adjacent offset ends of the tubes are spaced from one another to permit expansion of the exhaust gases therebetween.

A still further object of the invention is to provide a muffler of the above type, wherein the tubes extend through baffle plates which are secured thereto and to the muffler casing so as to

afford expansion chambers for the gases during their passage therethrough.

The above and other objects of the invention will in part be obvious, and will be hereinafter more fully pointed out.

In the accompanying drawing,

Figure 1 is a side view, in section, showing one form of the improved muffler assembly.

Figure 2 is a similar side view, in section, showing a modified form of the improved muffler assembly.

Figure 3 is a sectional view taken along the line 3—3 of Figure 1.

Figure 4 is a sectional view taken along the line 4—4 of Figure 2.

Referring more in detail to the accompanying drawing, and particularly to Figures 1 and 3, the muffler assembly is illustrated as including an outer muffler casing 10 which is provided with end closures 11, 12. The end closures 11, 12 are provided with outwardly extending flanges 11a, 12a, respectively, which are suitably secured, as by welding, to the inner surface of the muffler casing 10. The end closures are centrally apertured and are provided with inwardly extending flanges 11b, 12b, respectively, around the central apertures therethrough. An exhaust pipe 13 is provided with a reduced end portion 13a which is disposed adjacent and within the flange 11b of the end closure 11. A tube 14 has one end thereof disposed within the reduced end 13a of the exhaust pipe 13, and these parts are secured together and to the flange 11b by welding or the like.

Baffle plates 15, 16 are provided with outer flanges 15a, 16a, respectively, which are secured to the interior surface of the muffler casing 10 by welding or the like. These baffle plates 15, 16 are also centrally apertured and are provided with inner flanges 15b, 16b, respectively. The tube 14 extends through the apertures defined by the flanges 15b, 16b, and is secured thereto by welding or the like. The tube 14 is thus centrally located with respect to the muffler casing 10. A chamber 17 is thus provided between the end closure 11 and the baffle plate 15, and a similar chamber 18 is provided between the baffle plates 15 and 16. The tube 14 is perforated to provide communication with the chambers 17, 18. As illustrated in Figure 1, the tube is provided with sets of elongated slots 19 which afford communication between the tube and the expansion chambers.

An outlet tube 20 is secured to the flange 12b on the end closure 12 at the opposite end of the 55

muffler casing 10. This tube 20 extends within the muffler casing, and baffle plates 21, 22 are provided with outer flanges 21a, 22a, respectively, which are welded or otherwise secured to the 5 inner surface of the muffler casing 10. The baffle plates 21, 22 are also centrally apertured and are provided with inner flanges 21b, 22b, respectively. The tube 20 extends through the apertures defined by the inner flanges 21b, 22b and 10 is thus centrally located with respect to the muffler casing 10. The flanges 21b, 22b are secured to the tube 20 by welding or the like. A chamber 24 is thus provided around the tube 20 between the baffle plates 21, 22. A similar chamber 25 is 15 provided around the tube 20 between the baffle plate 22 and the end closure 12. Elongated slots 23 are provided in the tube 20 for affording communication with the expansion chambers 24, 25.

The tubes 14 and 20 are illustrated in Figure 1 20 as being in axial alignment, and the inner ends thereof are spaced apart a substantial distance, as are the baffle plates 16 and 21. Within the space between the inner baffle plates 16 and 21, a central tube 26 is located. Intermediate baffle 25 plates 28, 29, 30 are disposed within the space between the baffle plates 16, 21, and are provided with outer flanges 28a, 29a, 30a, respectively, which are secured to the inner surface of the muffler casing 10. The intermediate baffle plates 30 are provided with aligned openings therethrough and with inner flanges 28b, 29b, 30b surrounding these openings. The openings in the intermediate baffle plates are offset with respect to the openings in the baffle plates at the ends of the 35 muffler casing, and the tube 26 extends through these offset openings and is secured to the flanges 28b, 29b, 30b in any suitable manner. The tube 26 is thus offset with respect to the end tubes 14, 20. The intermediate baffle plates 28, 29, 30 40 define expansion chambers 32, 33, and the tube 26 is provided with elongated slots 27 which afford communication between the tube and these chambers.

The baffle plates 16 and 28 are spaced from 45 one another, as are the baffle plates 21 and 30, so that each end of the tube 26 is spaced from the adjacent end of the tubes 14 and 20. Thus, a chamber 31 is provided between the baffle plates 16 and 28, and a chamber 34 is provided between the baffle plates 21 and 30. Gases of combustion entering the tube 14 from the exhaust pipe 13 are successively expanded in the chambers 17, 18 during their passage through the tube 14. The elongated slots 19 in the tube 14 permit a rapid 50 expansion of the gases into the chambers 17 and 18. The gases issuing from the inner end of the tube 14 are further expanded in the chamber 31 between the baffle plates 16 and 28. The gases then pass through the offset central tube 26 and 55 are further expanded in the chambers 32, 33 by passing through the slots 27 in the tube 26. The gases issuing from the opposite end of the tube 26 are further expanded in the chamber 34 between the baffle plates 21, 30. From this chamber, the gases pass into the outlet tube 20 and 60 are finally expanded in the chambers 24, 25 during the passage thereof through the elongated slots 23 in the tube 20.

In the modified form of muffler assembly shown 65 in Figures 2 and 4, the muffler casing 10 is provided with end closures 35, 36 which are provided with outer flanges 35a, 36a, respectively, secured to the inner surface of the casing. The end closures 35, 36 are apertured at one edge thereof 70 and provided with inner flanges 35b, 36b, respec-

tively, around the apertures. At one end of the muffler casing, spaced baffle plates 37, 38 are provided with outer flanges 37a, 38a which are secured, as by welding, to the inner surface of the muffler casing. These baffle plates are also apertured in alignment with the aperture through the end closure 35, and a tube 39 extends through the apertures in the end closure 35 and the baffle plates 37, 38. The baffle plates 37, 38 are provided with inner flanges 37b, 38b, respectively, 10 which are secured around the tube 39, as is the flange 35b on the end closure 35. The tube 39 is provided with elongated slots 39a which communicate with chambers 40, 41 defined by the end closure and the baffle plates 37, 38. 15

Spaced baffle plates 42, 43 at the opposite end of the casing 10 are provided with outer flanges 42a, 43a, respectively, which are secured to the inner surface of the muffler casing 10. These baffle plates are also apertured in alignment with 20 the aperture in the end closure 36, and are provided with inner flanges 42b, 43b which are secured to a tube 44, as is the flange 36b on the end closure 36. The tube 44 is provided with elongated slots 44a which afford communication 25 with chambers 45, 46 defined by the end closure 36 and the baffle plates 42, 43. Thus, the tube 44 is illustrated as being in axial alignment with the tube 39 at the opposite end of the muffler casing, but it may be offset around the periphery 30 of the casing, if so desired.

The inner ends of the tubes 39, 44 are substantially spaced from one another, and the central portion of the muffler casing between the ends of these tubes is provided with spaced baffle 35 plates 47, 48, 49, the outer flanges 47a, 48a, 49a, respectively, being secured, as by welding, to the inner surface of the muffler casing. The intermediate baffle plates 47, 48, 49 are provided with aligned apertures around which inner flanges 40 47b, 48b, 49b, respectively, extend. These apertures are offset with respect to the apertures in the baffle plates at the ends of the casing, and a tube 50 extends through the apertures in the intermediate baffle plates and is secured to the 45 inner flanges 47b, 48b, 49b. As shown in Figure 2, the central tube 50 is offset with respect to the end tubes 39, 44 a greater distance than the offset shown in Figure 1. Thus, there is no overlapping of the central tube 50 with the end tubes 50 39, 44, as in the construction in Figure 1. The central tube 50 is provided with elongated slots 50a which communicate with chambers 51, 52 defined by the intermediate baffle plates.

The baffle plates 38, 47 are spaced from one another so as to provide an expansion chamber 53 between the adjacent ends of the tubes 39 and 55 50. Similarly, the baffle plates 42, 49 are spaced from one another to provide an expansion chamber 54 between the adjacent ends of the tubes 44 60 and 50. Exhaust gases entering the muffler through the tube 39 are successively expanded in the chambers 46, 44 by passing through the slots 39a. The gases issuing from the inner end of the tube 39 are further expanded in the chamber 53 65 and then pass into the central tube 50. During the passage of the gases through the tube 50, they are expanded into the chambers 51, 52 and are further expanded in the chamber 54 at the outlet end of the tube 50. The gases then pass into 70 the tube 44 at the opposite end of the muffler casing and are successively expanded in the chambers 45, 46 before passing out of the muffler.

There is thus provided a muffler which combines the advantageous features of a "straight- 75

through" type of muffler and the "tri-flow" type of muffler. The gases are caused to pass through the muffler casing in a sinuous path and are successively expanded into the expansion chambers defined by the spaced baffle plates during their passage through the muffler. This sinuous passage of the gases through the muffler casing is afforded by offsetting adjacent ends of the tubes within the casing, and the tubes are provided with elongated slots so as to assure rapid expansion of the gases in the successive expansion chambers afforded within the muffler casing.

It is to be clearly understood that various changes in the detail of construction and arrangement of parts may be made without departing from the scope of the invention as set forth in the appended claims.

I claim:

1. A muffler comprising a casing, a plurality of spaced baffle plates secured to the inner surface of said casing and affording a plurality of expansion chambers, a pair of perforated end tubes disposed within said casing and extending through a plurality of said baffle plates at each end of said casing for permitting the passage of gases into the expansion chambers defined by said baffle plates, said end tubes being disposed in axial alignment coincident with the axis of said casing and the inner ends of said end tubes being substantially spaced from one another longitudi-

nally of said casing, and a central perforated tube disposed within the casing in the space between the inner ends of said end tubes and having the axis thereof offset with respect to the axes of said end tubes, said central tube extending through baffle plates disposed in the intermediate portion of said casing for permitting the passage of gases into the expansion chambers defined by said baffle plates, the inner end of each of said end tubes and the adjacent end of said central tube being spaced from one another and disposed in an expansion chamber for permitting expansion of the gases when passing from one tube to another.

2. A muffler comprising a casing, a plurality of spaced baffle plates secured to the inner surface of said casing and affording a plurality of expansion chambers, and a plurality of tubes disposed within said casing and extending through a plurality of said baffle plates, the adjacent ends of said tubes being spaced from one another longitudinally of said casing, each of said tubes being provided with elongated longitudinal slots between adjacent baffle plates for permitting the gases to pass into the expansion chambers defined by said baffle plates, and at least one of said tubes being offset with respect to and adjacent pair of tubes for providing a sinuous path for the gases through the muffler casing.

HERBERT S. POWELL. 30
